US00D689649S

(12) **United States Design Patent**
Popper et al.

(10) **Patent No.:** **US D689,649 S**
(b4) **Date of Patent:** **** Sep. 10, 2013**

(54) **LENS**

(75) Inventors: **Richard S. Popper**, Scottsdale, AZ (US); **Jensen Jorgensen**, Scottsdale, AZ (US)

(73) Assignee: **XGlow P/T, LLC**, Scottsdale, AZ (US)

(**) Term: **14 Years**

(21) Appl. No.: **29/429,213**

(22) Filed: **Aug. 8, 2012**

(51) **LOC (9) Cl.** **26-99**

(52) **U.S. Cl.**

USPC **D26/124**

(58) **Field of Classification Search**

USPC D26/154, 155, 152, 142, 151, 153, D26/113, 119, 122, 123, 124, 138, 145, 148, D26/146, 147, 121, 125, 126, 74, 75, 144, D26/150, 141, 118, 120, 128, 129, 132, 135, D26/71, 72, 85, 62, 65, 64, 24, 1, 2, 66, 67, D26/68, 73, 89, 86, 87, 88, 25, 26, 61, 63, D26/69, 76, 77, 78, 79, 90, 91, 84, 92, 49, D26/37, 38, 39; D13/179, 180, 171, 173; D11/90, 121, 89; 63/32; 362/253, 257, 333, 362/326, 169, 187, 307, 327, 308, 309, 362, 362/337, 208, 158; 16/442; 359/708, 641, 359/726; D6/581; D9/452, 435, 453, 443
